(57) CLAIM

The ornamental design for a pedicure base station, as shown and described.

DESCRIPTION

FIG. 1 is a top side perspective view thereof,

FIG. 2 is a bottom side perspective view thereof,

FIG. 3 is a front side view thereof,

FIG. 4 is a back side view thereof,

FIG. 5 is a right side view thereof,

FIG. 6 is a left side view thereof,

FIG. 7 is a top side view thereof; and,

FIG. 8 is a bottom side view thereof.

The broken lines in the figures are for the purpose of illustrating portions of the pedicure base station, which form no part of the claimed design.
